UNITED STATES PATENT OFFICE.

MATHEW P. ZOSTAS, OF WORCESTER, MASSACHUSETTS.

COMBINATION FURNITURE.

Application filed January 7, 1927. Serial No. 159,725.

This invention relates to a piece of furniture which can be converted from a condition suitable for one use to a condition suitable for another. The principal objects of 5 the invention are to provide two relatively movable parts, one of which is adapted to be fixed and constitute the main part of the piece under all conditions and the other of which contains an essential element of the 10 piece of furniture into which it is to be converted, this essential element being movable backwardly, upwardly and then forwardly to bring it out of the recess in which it is normally located and into a position in 15 which it can be used. The invention involves details of the mechanism for accomplishing these motions. The invention also involves in its preferred form the combination of a bureau and desk so that it can be set up as 20 either one and without taking any of the parts off or getting them out of adjustment or alignment.

Other objects and advantages will appear hereinafter.

Reference is to be had to the accompanying drawings in which

Fig. 1 is a front view of a bureau constructed in accordance with this invention;

Fig. 2 is a side view showing the parts 30 drawn back to release an essential element of a desk;

Fig. 3 is a similar view showing the next operation in which the said element is raised;

Fig. 4 is a similar view showing this element as moved over on top of the bureau;

Fig. 5 is a front view of the desk with the parts in the position shown in Fig. 4; and

Fig. 6 is a front elevation of the bureau 40 back and mirror, taken on an incline as indicated by the arrow 6 in Fig. 2.

Describing the invention in the particular form shown, it will be seen from Fig. 1 that it is built in the form of a bureau 10. This 45 has the usual drawers 11 and 12 and is also provided with a mirror 13 supported by a false back comprising uprights 14 so that it has very little about it to show that it can also be converted into a desk.

50 It has a slide 15 adapted to move out in front when used as a desk. The uprights 14 extend clear to the bottom of the bureau and are pivoted near the bottom at 16. They are also cut in two and hingedly connected by 55 two hinges 17 at opposite sides of the bureau in the back. This allows the mirror 13 to

be swung over into the dotted line position shown in Fig. 2. For holding the upper portion of the uprights 14 in vertical position, a pair of hooks 19 are shown at the 60 front which co-operate with the hinges 17 at the rear to hold the mirror in vertical position.

It will be noted that the drawers 12 do not extend clear back to the rear of the 65 bureau but are far enough back to leave a space 20 at the rear in which is located an element 21 of the desk into which the bureau is designed to be converted. This element is in the form of a top having pigeon-holes 70 and drawers and the like, if desired, as indicated in Fig. 3 for example. This element is mounted on the uprights 14 so that it projects horizontally into the space 20 when these uprights are in their most forward 75 position.

The uprights are provided with pivoted racks 22 and are operated by pinions 23 on a shaft 24 extending through the bureau. The shaft has a handle 25 for turning it. 80

This can be turned as shown in Fig. 2 back to a certain limiting position. On these uprights are also a pair of racks 26 which engage a pair of pinions 27 on a cross shaft 28 having a crank handle 29 for operating 85 it. This cross shaft 28 is fixed on the element 21 and moves back with it. The turning of this crank 29 will raise the element 21 to the position shown in Fig. 3. Now the crank 25 can be turned back and the uprights 90 brought forward to bring the element 21 over the top of the bureau as shown in Fig. 4 so that with the draw-board 15 the bureau constitutes a desk. The mirror can be brought down as shown at the rear in a 95 vertical position for storage or shipping.

The operation of the device has been described and it will be seen that it can be formed into a bureau with nothing to show any combination about it except the two 100 crank handles 25 and 29, which are at the end in an out of the way place, and the front end of the slide 15. When converted into a desk it has all the conveniences for that purpose and it is as useful as any ordinary desk. Furthermore, the papers and loose articles put in the pigeon holes in the element 21 do not have to be taken out or displaced in any way when it is converted back into a bureau. The only space that is lost in the bureau is 110 the space 20. A typewriter 30 can take the place of the middle drawer 12.

Although I have illustrated and described only a single form of the invention I am aware of the fact that modifications can be made therein by any person skilled in the art without departing from the scope of the invention as expressed in the claims.

Therefore, I do not wish to be limited to all the details of construction herein shown and described, but what I do claim is:—

- 10 1. As an article of manufacture, a piece of combination furniture comprising a main portion having strips at the rear pivoted thereto and projecting above the top of said main portion, the main portion having a recess in the rear and an element constituting a part of another article of furniture normally housed in said recess and carried by the pivoted strips and pivotally movable therewith backwardly away from the main portion and straight upwardly with respect thereto, remaining the same side up, thereon into a position on the top of the main portion.
- 15 2. As an article of manufacture, a piece of combination furniture comprising a stationary member having uprights at the rear pivoted at the bottom and projecting above the top of said stationary portion, the stationary portion having a recess in the rear near the top and an element constituting a part of another article of furniture normally housed in said recess and secured to the pivoted uprights and movable therewith and thereon into a position on the top of the stationary member.
- 20 3. In an article of furniture, the combination with a bureau frame having drawers therein and a pair of uprights movable backwardly thereon, said frame having a recess in the back, of a desk element normally located in said recess and connected with said uprights to move back entirely out of the recess when the uprights move back, and mechanical means for moving said desk element upwardly along the uprights, so that, when the uprights are swung forward, the desk element will move over the top of the bureau to convert the bureau into a desk.
- 25 4. In a combination bureau and desk, the combination with a bureau frame having drawers therein, a pair of uprights pivoted to the back thereof and extending above said bureau drawers and a mirror supported thereon, said frame having a recess in the back near the top, of a desk element comprising

ing pigeon-holes normally located in said recess and connected with said uprights to move back out of the recess when the uprights are swung back on their pivots, and means for moving said desk element upwardly along the uprights when swung back, so that when the uprights are swung forward again the desk element will swing over the top of the bureau and remain in place thereon to convert the bureau into a desk. 65

5. As an article of manufacture, a bureau having a false back pivoted near the bottom and at the back, and a mirror carried thereby at the top, fixed racks on said back, a pigeon-hole structure having a shaft therethrough provided with a pair of pinions meshing with the racks and supported by the back, means for moving the back to and fro, and a crankshaft on said pigeon-hole structure for raising and lowering the pigeon-hole structure so as to place it above or below the top of the bureau and in the former place convert the bureau into a desk. 70

6. In a combination bureau, the combination with a bureau proper having lower drawers and a set of upper drawers reaching only part way back into the bureau to leave a recess, of a pair of uprights pivoted to the rear of the bureau at the bottom, said uprights having lower and upper portions, 80 the latter being hinged to the lower portion so as to swing over backwardly therefrom, pigeon holes carried by the uprights and normally located in the recess, the hinges being on the rear surfaces of the uprights, 85 and hooks on the front surface co-operating with the hinges to hold the uprights rigidly in extended position when the hooks are engaged. 90

7. In a bureau, the combination with a frame, lower drawers and a set of upper drawers, of a pair of uprights pivoted to the rear of the bureau at the bottom and divided into upper and lower portions, the upper portions of said uprights being hinged to the 100 lower portion so as to swing over backwardly therefrom, a mirror carried by the upper portions of the uprights, the hinges being on the rear surfaces of the uprights, and hooks on the front surface co-operating with the hinges to hold the uprights rigidly in extended position when the hooks are engaged. 105

In testimony whereof I have hereunto affixed my signature.

MATHEW P. ZOSTAS.
